Fig. 1.

UNITED STATES PATENT OFFICE.

GEORGE W. WRIGHT, OF LAPEL, AND RAYMOND W. NICHOLS, OF KOKOMO, INDIANA.

AIR-PUMP.

1,380,878.

Specification of Letters Patent. Patented June 7, 1921.

Application filed June 21, 1920. Serial No. 390,385.

To all whom it may concern:

Be it known that we, GEORGE W. WRIGHT and RAYMOND W. NICHOLS, citizens of the United States, residing at Lapel, in the 5 county of Madison and State of Indiana, and Kokomo, in the county of Howard and State of Indiana, respectively, have invented a new and useful Air-Pump, of which the following is a specification, reference being had to 10 the accompanying drawings, and to the figures of reference marked thereon.

This invention relates to a pump of the reciprocatory type, such as a single-acting portable pump, the invention having reference 15 to pump construction generally and especially to the piston or plunger in pumps of the above-mentioned character.

An object of the invention is to provide an efficient and reliable pump of such construction as to be adapted for pumping and compressing air, and not liable to receive dust-laden air from a floor or ground and become damaged or deranged in use or when roughly or carelessly handled.

Another object is to provide an improved 25 air-pump which shall be of simple and inexpensive construction, and which will be highly efficient and durable and economical in use; an aim being to so construct the pump 30 as to permit it to be readily repaired in case of necessity and to renew parts worn out by long use.

With the above-mentioned and other objects in view, the invention consists in an 35 improved air pump having various novel features, and especially in relation to means adapted to insure effective operation in compressing air; and the invention consists also further in the novel parts and combinations 40 and arrangements of parts, as hereinafter particularly described and further defined in the accompanying claims.

Referring to the drawings, Figure 1 is a vertical central section of a pump constructed substantially in accordance with the invention; Fig. 2 is a perspective view of the improved air-pump; Fig. 3 is a transverse section of the pump cylinder and bottom plan of the pump piston minus the valve 50 thereof; and, Fig. 4 is a fragmentary longitudinal section in which the valve of the piston is shown in open position.

Similar reference characters in the different figures of the drawings indicate corresponding parts or features of construction herein referred to in detail.

A practical embodiment of the invention, illustrated as a portable air-pump, comprises a base 1 having a central socket wall 2 thereon, one portion of the wall having a boss 3 thereon in which is a port 4, the boss having a valve chamber 5 extending to the port and in which a spherical valve 6 is arranged for properly closing the port, the valve being retained in the valve chamber by means of a cage 7 screwed into the chamber and having a nipple 8 thereon. The cage and nipple has an outlet channel 9 therein for the discharge of air; and as used for a tire pump and for some other purposes a flexible tube 10 is connected to the nipple. The wall 2 preferably has screw threads 11 therein. A hollow cylinder or barrel 12, is provided and secured to the base, preferably being provided with screw threads 13 connected with the threads 11, so that the base constitutes a closure for the lower end of the cylinder. The upper or opposite end of the cylinder is provided with a cap or head 14 which is secured to the cylinder, preferably by means of screw threads 15 therein engaging threads 16, cut on the cylinder. The cap has a vent or air hole 17 therein and also a central guideway 18.

A hollow or tubular pump rod 19 is provided and arranged for longitudinal movement in the guideway 18, and preferably has an annular valve seat 20 on its lower end and also external screw threads 21 extending from said end. A pump piston is secured to the pump rod and comprises a nut 22 screwed on the rod, a head plate 23 arranged against the nut, being cheaply made as a separate part, and a cup packing of suitable material comprising a disk 24 having an expansible rim flange or ring 25 thereon and fitted to the cylinder, the disk being against the head plate. A follower plate 26 is placed on the pump rod against the disk 24 and a nut 27 is screwed onto the pump rod against the follower plate. The flange 25 has a beveled or conical valve seat 28 on its end adapted to be engaged by a valve. The pump rod has screw threads 29 extending from its opposite or outer end and a nut 30 is arranged thereon, a washer 31 preferably being placed against the nut. A handle bar 32 is placed on the pump rod against the washer, having a central aperture 33 receiving the rod; a washer 34 is placed on the rod against the handle bar and a nut 35 is screwed onto the rod against the washer. A rod or pin 36 is

105
110

arranged in the pump rod in suitable openings so as to extend across the interior of the pump rod adjacent to the outer end of the rod. Preferably an annular cap 37 is secured on the pump rod to cover the nut 35 and projecting ends of the rod 36.

A novel device is provided which constitutes a valve and also a packing expander, and it comprises a disk 38 having a bevel edge or valve portion 39, the disk being smaller in diameter than the cylinder 12 to permit the flow of air past it, and the valve portion is adapted to be seated on the valve seat 28 and to expand the flange 25 closely to the wall of the cylinder 12 to prevent leakage of air past the flange. The packing cup, in order to be durable, is composed of firm material, such as hard leather, or fibrous compositions. The disk is adapted to be seated also on the valve seat 20 after the valve has expanded the packing flange, and in some cases the adjustment or proportion may be such as to permit contact of the valve with the seat 20 only after considerable use and consequent wear of the packing, to insure proper valve action in case of leakage past the valve seat 28. The disk 38 has a stem 40 rigid thereon which extends into the pump rod 19 and has an eye 41 adjacent to its end, the stem being sufficiently thin to permit free passage of air through the pump rod. A coil spring 42 is arranged in the pump rod and has a stem 43 which is connected in the eye 41 with the stem 40, the spring having a stem 44 on its opposite end. The spring stem 44 may be variously anchored to the rod 19 but preferably has an extension stem which preferably is composed of a separate rod 45 having an eye 46 which is connected to the stem 44, and having also an eye 47 connected with the rod or cross-bar 36 to place the spring slightly under tension sufficient to prevent the valve disk 38 from loosely falling away from its valve seat.

In practical use the tube or conduit 10 is properly connected with a pneumatic tire or otherwise where compressed air is to be delivered, the base 1 may be secured in a permanent position or may be held down by the feet of the operator who operates the pump rod 19 by means of the handle bar 32; or obviously the pump rod may be otherwise operated. As the pump rod is moved to draw the piston away from the base, partial vacuum is created between the valve disk 38 and the base and causes the valve 6 to be seated, if not seated by gravity, and the valve disk is unseated and permits clean air to pass through the pump rod and past the valve and into the lower portion of the pump cylinder, air which may be in the upper portion of the pump cylinder, flowing past the packing flange or escaping through the vent 17. When the motion is reversed

and the piston forced toward the base the valve disk is seated on the valve seat 28 and not only prevents air from escaping back through the pump rod but expands the packing flange 25 against the cylinder wall, 70 so that the piston causes compression of the air in the cylinder and forces it through the port 4 and into any receptacle with which the pump may be connected, further operation of the pump causing the air to be 75 compressed in the tire or receptacle.

Having thus described the invention, what is claimed as new is—

1. A pump including a hollow cylinder, a piston head in the cylinder, a pump rod in 80 the cylinder having a hollow portion extending through and rigidly secured to the piston head, the end of the hollow portion being open, a packing ring on the piston head in connection with the cylinder, a valve removably arranged on the packing ring and the open end of the pump rod, and a spring having connection with the valve and the pump rod and tensioned to yieldingly hold the valve in place. 90

2. A pump including a hollow cylinder, a piston head in the cylinder, a pump rod guided in the cylinder and having a hollow portion extending through and rigidly secured to the piston head, the end of the hollow portion being open, a packing ring on the piston head in connection with the cylinder, a spring in the hollow portion of the pump rod and having one end connected to the rod, a valve stem loose in the hollow portion of the pump rod opposite to the opposite end of the spring and connected to the spring, and a disk valve fixed on the valve stem and in removable connection with the packing ring, the valve extending 100 across and adjacent to the open end of the pump rod and being yieldingly held in place by the spring. 105

3. In an air-pump, the combination of a base, an outlet valve arranged in the base, 110 a hollow cylinder secured at one end to the base, a guide cap secured to the opposite end of the cylinder, a piston head in the cylinder, a pump rod guided in the cap and having a hollow portion extending through and secured to the piston head, the end of the hollow portion being open, a packing ring secured to the piston head in connection with the cylinder and having a beveled edge to constitute a flexible valve seat, a disk valve 115 having a beveled edge to coöperate with said valve seat and being adapted to coöperate with said open end of the pump rod, said valve having a stem thereon extending into said pump rod, and a coiled spring connected with said stem and with the pump rod and tensioned to yieldingly hold the valve to the packing ring. 120

4. In an air-pump, the combination of a base, an outlet valve arranged in the base, 130

- hollow cylinder secured at one end to the base, a cap secured to the opposite end of the cylinder and having a central guideway and also a vent hole therein, a tubular pump rod movable in said guideway and having a valve seat on its inner end and a cross-bar adjacent to its outer end, two nuts on the pump rod in proximity to the inner end thereof, a piston head and a follower between the nuts, a packing disk between the piston head and the follower and having a rim flange thereon arranged against the cylinder, the rim flange having a beveled edge to constitute a valve seat, a disk valve having a beveled edge to operate on the bevelled edge of said flange, the disk valve being adapted to coöperate with the valve seat on the end of said pump rod and being provided with a stem extending into said rod, a coiled spring connected with said stem 20 and with said cross-bar, and a handle bar secured to said pump rod adjacent to said cross-bar.
